UNITED STATES PATENT OFFICE.

CHARLES FAWCETT BENNION, JOSEPH GOULBOURN, AND ARTHUR BATES, OF LEICESTER, ENGLAND, ASSIGNORS TO UNITED SHOE MACHINERY CORPORATION, OF PATERSON, NEW JERSEY, A CORPORATION OF NEW JERSEY.

MACHINE FOR SHAPING UPPERS OVER LASTS.

Application filed September 13, 1920. Serial No. 409,920.

To all whom it may concern:

Be it known that we, CHARLES F. BENNION, JOSEPH GOULBOURN, and ARTHUR BATES, residing at Leicester, Leicestershire, 5 England, have invented certain Improvements in Machines for Shaping Uppers Over Lasts, of which the following description, in connection with the accompanying drawings, is a specification, like reference 10 characters on the drawings indicating like parts in the several figures.

This invention relates to machines for use in the manufacture of boots and shoes for shaping uppers over lasts. In some of its 15 features the invention has particular advantages as applied to pulling-over machines, and it is herein shown in its application to a well-known type of machine the general organization of which is shown and 20 described in United States Letters Patent No. 1,029,387, granted on June 11, 1912 upon an application of R. F. McFeely. It is to be understood, however, that in many of its 25 aspects the invention is not limited to machines of the particular type illustrated.

An object of the invention is to provide for closer conformation of an upper to its last and more effective stretching of the upper than has been characteristic heretofore of power machines having a determinate cycle of operations. Experience has demonstrated that for many kinds of uppers and differing styles of lasts a mere continuous and progressive relative movement between the last and the upper gripping means is not always sufficient to conform the upper closely to the last or to take the stretch fully out of the upper. It has accordingly been the practice in the operation, for example, of pulling-over machines of the type shown in said prior patent, for the operator, after the machine has come to a stop with the upper under tension, to move one or more of the gripper levers to vary the lateral or lengthwise tension of the upper, thus completing the stretching and conforming of the upper to the last as observation shows to be necessary. The present invention, in one of its important aspects, contemplates 45 an organization whereby the operator will be relieved entirely or for the most part of the necessity of performing such subsidiary operations.

With the above and other objects in view, a feature of the invention consists in a novel 55 organization of means for conforming an upper to a last by a plurality of relative movements between the last and means which grips the margin of the upper. In one of its aspects the invention contemplates 60 a novel combination of initial upper pulling means and supplemental means having a determinate cycle of tension relaxing and tension applying movements to work the upper progressively into conformity to the 65 contour of the last. The illustrative construction comprises supplemental gripper operating means connected both to the toe gripper and to the side grippers and arranged for operation after the upper has 70 been initially pulled to move all the grippers in unison first to relax the tension of the upper and then to increase the tension, and it may be to apply a final tension greater than that under which the upper was first 75 pulled. In the machine shown the supplemental gripper operating means is arranged to be started in operation at the will of the operator after the machine has come to a stop with the upper held under the initial 80 tension and further comprises mechanism for imparting to the grippers positive tension relaxing and tension applying movements. It is to be understood, however, that in many of its aspects the invention is not 85 limited to the illustrative manner of control, nor to an organization in which all the grippers are operated in unison or in which the tension relaxing and tension applying movements are, in character and sequence, 90 precisely as herein illustrated.

A further feature of the invention resides in a novel organization of upper pulling means and controlling means for determinately varying the number of operations of 95 the upper pulling means. In its embodiment of this feature, the machine shown is provided with controlling mechanism whereby the operator is enabled to start the operation of the supplemental gripper operating 100 means as many times as desired or to continue it in operation as long as desired while the upper is still under tension. In this manner the operation of the machine may be accommodated to the particular character 105 of the work under treatment, and as good

2 results may be secured with difficult work as with work which responds readily to the upper tensioning pull.

As applied to a machine in which the grippers are operated yieldingly through springs which may assume different degrees of tension proportional to differences in resistance of different portions of the upper, the invention provides, as a further feature, novel means designed to prevent a balancing action between different springs with a consequent tendency to displace the upper on the last. Such means has particular advantages in an organization including supplemental gripper operating means as herein shown, wherein it is desirable to impart to different grippers supplemental movements of substantially equal extent without substantially altering the relation assumed by the different grippers in the initial upper pulling operation. In the illustrative machine the supplemental movements are conveniently imparted to the opposite side grippers from a single operating member through connections which are relatively movable in proportion to differences in the initial movements of the different grippers, and as applied to such an organization the invention provides means whereby the operating connections for the grippers are arranged to compensate automatically for differences in the compression of the respective gripper springs. More particularly, in the construction shown the side gripper levers are connected by links to opposite arms of a pivoted lever which is moved bodily to impart to the grippers their supplemental movements, and said lever arms are so arranged that their effective lengths are altered in proportion to differences in compression of the different springs and in such manner as to compensate for such differences of compression. This arrangement, supplementing the normal friction of the different parts, serves to guard against such balancing action of the springs as might occur for example when the grippers are moved to relax the force of the pull on the upper.

Still another feature of the invention consists in novel means for effecting relative movement of different grippers for adjusting the upper, the machine shown having manual means arranged to operate through the supplemental operating connections for the side grippers to move said grippers simultaneously in opposite directions for adjusting the upper transversely. Advantageously in the construction shown the means which assists, as above explained, in preventing relative balancing movement between the opposite side grippers co-operates also with the manual adjusting means to assist in maintaining the grippers in adjusted relation. Still further to assist in

70 maintaining such relation of the grippers, the machine shown is provided with a friction device associated with the manual adjusting means and tending to prevent its displacement.

75 The above and other features of the invention, including certain details of construction and combinations of parts, will now be described with reference to the accompanying drawings and pointed out in 76 the claims.

In the drawings,—

Fig. 1 is a view in side elevation of the head portion of a pulling-over machine in which the invention is embodied;

80 Fig. 2 is a side elevation showing in more detail than Fig. 1 the supplemental mechanism with which the machine is provided for imparting operative movements to the grippers;

85 Fig. 3 is a view of the head portion of the machine in rear elevation, and

Fig. 4 is a side elevation, with parts in vertical section, showing the driving and controlling mechanism for the supplemental 90 gripper operating means.

95 Since the features common to the machine herein shown and to prior machines of the illustrative type are shown and described in detail in prior patents including Patent No. 1,029,387 above mentioned, such features will be described herein only in as far as is necessary for an understanding of the present invention.

100 Machines of this general type include in their organization a toe gripper 2 and opposite side grippers 4 connected respectively to an intermediate updraw lever 6 and to opposite side updraw levers 8, these levers at their rear ends having swiveled 105 connections with blocks 10 slidingly mounted on tension rods 12 provided with springs 14 which bear downwardly on the blocks and are engaged at their upper ends by adjustable tension nuts 16 on the rods. The 110 rod 12 for the toe gripper lever is fixed to a vertically movable cam slide 18 and the rods 12 for the side gripper levers are fixed to a similar cam slide 20, these cam slides 115 being operated by the usual updraw cams which are mounted on a cam shaft 22. It will be understood that upon the starting of the machine, with a shoe presented with the margin of its upper extending within the open gripper jaws, the cam shaft 22 makes a partial revolution, imparting downward movement to the cam slides 18 and 20 to close the grippers on the upper and then through the springs 14 to impart pulling movement yieldingly to the grippers, 120 thereby effecting a relative separation between the upper ends of the cam slides and the blocks 10 proportional to the compression of the springs, as shown in Fig. 2. The rotation of the cam shaft is then 125 130

- stopped by the automatic action of the usual starting and stopping means, including a brake shoe 24 which engages the driving pulley 26, to enable the operator to inspect 5 the work while the upper is held under tension and to make any adjustments in order to correct the position of the upper on the last or to vary the longitudinal or the transverse tension under which the upper is held.
- 10 Upon the subsequent starting of the machine, overlaying and fastening devices for the toe and for the opposite sides of the forepart, mounted respectively on a front arm 28 and on opposite side arms 30, are 15 operated to wipe the margin of the upper inwardly and to fasten it to the sole or insole, the toe and side grippers at the same time receiving their overdraw movements and being finally tripped to release the 20 margin of the upper. The parts of the machine are then returned to their starting positions, the cam shaft coming to a stop at the end of a complete revolution.
- 25 For the purpose of imparting supplemental movements to the toe and side grippers after the machine has come to rest with the upper held under tension, in order to stretch the upper more effectively and to work it into better conformity to the contour 30 of the last, the machine herein shown is provided with an auxiliary cam shaft 32 mounted on a bracket 34 secured on the rear of the head portion of the machine, this shaft in the construction shown being operated and controlled independently of the driving and controlling means for the main cam shaft 22 by means to be hereinafter described. The rear ends of the side updraw levers 8 are connected by links 36 respectively to oppositely disposed arms 38 and 40 of a lever member which is pivoted at 42 on an operating lever 44, the lever 44 being pivoted in turn at 46 on the bracket 34 and having an upwardly extending arm 45 provided with a roll 48 to co-operate with a cam 50 on the cam shaft 32. It will be evident by reference to Fig. 2 that the cam 50 is arranged, by engagement with the roll 48, to swing the lever 44 about its pivot 46 in the direction to pull upwardly on the links 36 and thus to swing the gripper levers 8 in the direction to relax the tension of the upper. Fast on the cam shaft 32 is also an edge cam 52 which is arranged to act 55 on a lever 54 mounted on the pivot 46 and held against the cam by a spring 56, this lever carrying a pawl 58 for engagement with ratchet teeth 60 on the rearwardly extending arm of the lever 44 to swing the lever 50 in the direction for imparting upper tensioning movement to the side grippers when the cam 52 swings the lever arm 54 downwardly. It will be noted by reference to Fig. 2 that the cam 52 is notched adjacent to its high portion and that in the 60 normal stopping position of the shaft 32 a projection 62 on the lever 54 is positioned in said notch, the lever being held by its spring in its uppermost position. In this position of the lever a stop screw 64 engages an arm 66 of the pawl 58 and holds the pawl, against the tension of its spring 68, out of engagement with the ratchet teeth 60.
- 65 For imparting supplemental movement to the toe gripper, the updraw lever 6 at its rear end is connected by a link 70 to a lever arm 72 which is pivotally mounted at 74 on the bracket 34 and is rigidly connected to a lever arm 76 which carries a roll 78 to be 70 engaged by a cam 80 on the cam shaft 32 for imparting to the toe gripper movement in the direction to relax the tension of the upper. For imparting to the toe gripper, similarly to the side grippers, movement alternately in the direction to increase the tension of the upper, there is mounted also on the pivot 74 a lever arm 82 in position to be 75 engaged by a cam 84 on the cam shaft 32, this lever being rigidly connected to an upwardly extending lever arm 86 provided with a pawl 88 for engagement with ratchet teeth 90 on the arm 76 to move this arm in the direction to depress the rear end of the gripper lever 6. A spring 92 connected to 80 the arm 86 holds the arm 82 against its cam. It will be noted that in the stopping position of the shaft 32 the end of the arm 82 is seated in a notch formed in the cam 84 adjacent to its high portion, and in this position of the parts the pawl 88 is held out of 85 engagement with the ratchet teeth 90 against the tension of its spring 94 by the action of a link 96 pivoted at 98 on the bracket 34 and having a slot 100 to receive a pin 102 on an 90 arm 104 of the pawl. It will be noted that the pawl 88, like the pawl 58 of the side gripper operating mechanism, is of double formation, that is, comprises two members with their ratchet engaging ends slightly 95 displaced one from the other to render the pawl more precise in its action on the ratchet teeth.
- 100 In the starting position of the machine the levers 44 and 76 are held, through their link 105 connections to the gripper levers, in such position that the rolls 48 and 78 are spaced from their respective cams a sufficient distance to allow for any normal movement of the gripper levers through the action of the cam slides 18 and 20 in the main upper pulling operation. The drawings show the machine with the parts positioned as they 110 are in the period of rest at the end of the main upper pulling operation, the rolls 48 and 78 having been moved from their first position toward their respective cams. If 115 the operator now actuates the starting means for the cam shaft 32, the cams 50 and 80 are turned into position to engage the rolls 48 120 and 78 respectively. The pawl 88 is held 125 out of engagement with the ratchet teeth 90 by the action of the link 96 pivoted at 98 on the bracket 34 and having a slot 100 to receive a pin 102 on an arm 104 of the pawl. It will be noted that the pawl 88, like the pawl 58 of the side gripper operating mechanism, is of double formation, that is, comprises two members with their ratchet engaging ends slightly 130 displaced one from the other to render the pawl more precise in its action on the ratchet teeth.

and 78 and through the lever and link connections described to move the toe and side grippers positively in the direction to relax the tension of the upper. As the cams continue their movement, they release the rolls and permit the updraw springs 14 again to act on the gripper levers to impart upper pulling movement yieldingly to the grippers. Finally the cams 52 and 84 arrive in position 10 to act on the respective levers 54 and 82, and by the movement of these levers the pawls 58 and 88 are released to permit their springs to force them into engagement with the ratchet teeth 60 and 90 and are rendered operative on the ratchet teeth to impart to the lever and link mechanisms movements in the reverse direction from those effected by the cams 50 and 80 to move the gripper levers positively in the direction to increase 15 the tension of the upper. Supplemental movements are thus imparted to the gripper levers first positively in the direction to relax the tension of the upper and then in the direction to increase the tension, the movements in the latter direction being first 20 yielding and then positive. It will be understood that the cams on the shaft 2 may be variously arranged for imparting movements in any desired sequence to the respective toe and side grippers, the cams in the 25 construction shown being arranged to operate the different grippers substantially simultaneously for relaxing and for increasing the tension. It will also be understood 30 that by adjusting the stop screw 64, and by adjusting the link 96 relatively to its pivotal mounting 98, the time of engagement of the different pawls with the respective ratchet teeth may be varied to increase or diminish 35 the extent of positive pulling movement imparted to the grippers by the action of the pawls. The extent of relaxing movement of the grippers effected by the cams 50 and 80 also may be varied by the adjustment of eccentric studs 106 and 108 on which the rolls 40 48 and 78 are respectively mounted. At the end of the revolution of the cam shaft 2 the members 54 and 82 are permitted by their cams to spring upwardly to render the screw 64 and the link 96 effective to swing the pawls away from their ratchet teeth, thus 45 releasing the grippers from the pawls to permit manual movements of the grippers, if desired, as well as to permit the gripper levers to be returned ultimately to starting 50 position without interference of the pawls.

In the operation of the side gripper levers 8 the respective tension springs 14, as is well understood, may be differently compressed, 55 depending on differences in resistance as between the opposite side portions of the upper, and it is desirable that such difference of compression be maintained in the supplemental movements of the grippers in order 60 that such movements may be substantially

equal in extent for both the side grippers and in order to prevent a shifting movement of the upper on the last by the balancing action of the updraw springs. For this purpose the lever arms 38 and 40 are so arranged 70 that a line connecting the points of pivotal connection of these arms with the links 36 passes above the axis of the pivot 42. As a result of this construction a variation in the effective lengths of the lever arms 38 and 40 75 takes place in proportion to any difference in the extent of updraw movements of the opposite side levers 8. The lever arms 38 and 40 are so arranged that when the rear ends of the side updraw levers are in substantially the same horizontal plane with their updraw springs under substantially the same stress the effective lengths of the arms are substantially equal. As a result, however, of a difference in the extent of the 80 upper pulling movements of the levers 8, with the resulting difference in compression of the respective springs 14, the lever arm 38 or 40 which is connected to the updraw lever which is under the greater spring tension 85 assumes a position in which its effective length is less than that of the other arm, as will be readily understood. In this manner a compensating action is provided for to insure against a balancing action of the side 90 updraw springs during the supplemental gripper movements. It will be understood that when the grippers release the upper the springs 14 force the rear ends of the 95 gripper levers downwardly until the blocks 10 engage the cam slide 20, thus re-establishing the normal relation with respect to effective length of the arms 38 and 40.

In order to enable the operator conveniently to shift the forepart of the upper 100 transversely of the last, either before or during the operation of the cam shaft 32, as is frequently desirable in order to position the upper correctly in relation to the last, the machine is provided with a hand lever 110 105 which is fixed on a lever arm 112 pivoted at 114 on the frame of the machine, the arm 112 being connected by a link 116 to an arm 118 which is pivotally mounted at 42 on the lever 44 and is rigidly connected to lever 110 110 arms 38 and 40. By movement of the hand lever 110 the operator may thus impart movement in one direction to one of the side grippers and a simultaneous movement in the opposite direction to the other gripper 115 to shift the upper laterally, the direction of the shifting movement of the upper depending upon the direction of movement of the lever 110. It will be evident that by reason of the compensating arrangement above described, assisted by the normal friction of the parts, the side gripper levers tend to remain in the positions which they assume 120 in response to the movement of the lever 110. As a further means for insuring 125

against balancing action of the opposite side gripper springs, a friction block 120 is secured to the lever arm 112 and is mounted for sliding movement in engagement with a 5 bar 122 which is pivotally mounted on the head of the machine. It will be evident that differences in movement as between the opposite side levers 8 necessarily involve a movement of the lever 110 and an accompanying 10 movement of the block 120 along the bar 122, and that the friction block by its action on the bar assists in maintaining the differential relation of the side gripper levers. It will also be evident that the arrangement 15 of the link 116 is such that movement of the lever 44 about its pivot 46 has substantially no effect upon the position of the hand lever 110.

The operating means for the cam shaft 32 comprises a horizontal driving shaft 124 mounted in bearings in the bracket 34 at one side of the machine, this shaft having a spiral gear 126 in engagement with a co-operating gear 128 on the shaft 32 to drive 25 the latter at a considerably lower rate of speed than the shaft 124. The shaft 124 may be driven through any suitable clutch mechanism, the construction shown comprising a clutch constructed and operated substantially 30 as shown and described in United States Letters Patent No. 1,124,620, granted on January 12, 1915, upon an application of A. E. Jerram. Briefly stated, this clutch comprises a driving pulley 130 having a 35 clutch ring 132, and a co-operating clutch member 134 keyed to a hub on the shaft 124 and slidable lengthwise of the shaft. The clutch member 134 has at one end a clutch ring 136 to co-operate with the ring 132 on the pulley and at its other end a friction ring 138 arranged for engagement with a stationary brake member 140. Springs 142 tend to move the member 134 into clutching 40 engagement with the pulley. Between its opposite ends the member 134 is provided with a peripheral groove 144 in a plane oblique to the axis of the shaft 124, and seated in this groove are opposite ring segments 146 which are pivoted to the ends of a yoke 45 member 148, the yoke member having a depending stem 150 journaled in a pendent lever 152 which is mounted on a horizontal pivot 154. The points of pivotal connection of the ring segments 146 with the yoke member 148 are slightly below the axis of the shaft 124, and by reason of this arrangement the yoke member 148 is not only oscillated about the axis of its stem 150 by the turning movement of the clutch member 134, 50 but is also oscillated lengthwise of the shaft 124, imparting swinging movement to the lever 152 about its pivot 154. As long as the lever 152 is thus permitted to oscillate about its pivot the clutch member 134 is 55 held by its springs in clutching engagement

with the pulley. To open the clutch and stop the rotation of the shaft 124 it is only necessary to stop the oscillatory movement of the lever 152 and to hold it in position to render the ring segments effective in the groove 144 70 to wedge the member 134 away from the pulley and into engagement with the brake member.

For controlling the clutch in the manner above described the machine is provided 75 with a pair of toggle links 156 and 158 connected together by a pivot 160 and pivotally mounted respectively on a bracket arm 162 and on a depending portion of the lever 152. A spring 164 connected to a lug on the link 156 serves to hold the links normally in straightened position determined by a stop screw 166. In this position of the parts the brake is applied, as shown in Fig. 4, and the auxiliary cam shaft 32 is idle. For actuating the clutch to start the rotation of the shaft 32 the machine is provided with a treadle (not shown) connected by a treadle rod 168 to the same lug on the toggle link 156 to which the spring 164 is connected. When the rod 168 is moved downwardly to break the toggle, the springs 142 are permitted to act to close the clutch, and the cam shaft 32 will then be driven as long as the toggle is broken to permit oscillatory movement of the lever 152. As further means of control, to insure that the shaft 32 shall make a complete revolution even though the operator may remove his foot immediately from the starting treadle, a link 170 is connected at its upper end to an eccentric pin on the end of the shaft 32 and at its lower end has nuts 172 arranged to bear upwardly 80 under an extension of the toggle link 156. 85 As soon as the shaft 32 starts to turn, upward movement is imparted to the link 170 and the nuts 172 are thus rendered effective to hold the toggle in broken condition even though the operator removes his foot from the treadle. As the shaft completes its 90 revolution downward movement of the link 170 permits the toggle to resume its straightened condition through the action of the spring 174 and thus to stop the oscillation of the lever 152 and cause the opening of the clutch. Automatically operative means is thus provided to stop the auxiliary gripper operating means at the end of a 95 single revolution of the shaft 32 if the operator removes his foot from the treadle. If 100 desired, however, the operator may hold the treadle depressed in such manner as to maintain the toggle in broken condition to cause the cam shaft 32 to make as many revolutions as may be desired. Alternatively, of 105 course, the operator may, after the shaft 32 has come to a stop, again actuate the clutch to cause a repetition of the supplemental gripper movements.

Having described the invention, what we 110

claim as new and desire to secure by Letters Patent of the United States is:

1. In a machine of the class described, the combination with means for gripping an upper on a last, and means for effecting relative movement of said gripping means and the last to pull the upper, of supplemental power driven means arranged to be started in operation after the upper has been pulled and constructed to effect a plurality of relative movements of said gripping means and the last in time relation for relaxing and increasing alternately the tension of the upper. 70
2. In a machine of the class described, the combination with means for gripping an upper on a last, and means for effecting relative movement of said gripping means and the last to pull the upper, of independently operative power means for effecting subsequently additional relative movements of said gripping means and the last, said power means having a determinate cycle of movements for alternately relaxing and increasing the force of the pull on the upper. 80
3. In a machine of the class described, the combination with means for gripping an upper on a last, and means for effecting relative movement of said gripping means and the last to pull the upper, of supplemental power operated means arranged for optional use after the upper has been pulled and having a determinate cycle of movements for relaxing and increasing alternately the tension of the upper. 90
4. In a machine of the class described, the combination with means for gripping an upper on a last, and means for effecting relative movement of said gripping means and the last to pull the upper, of supplemental power operated means for effecting subsequently a plurality of relative movements of said gripping means and the last in time relation for relaxing and increasing alternately the tension of the upper, and controlling means enabling the operator to determine the time interval between the first upper pulling operation and the operation of said supplemental means. 100
5. In a machine of the class described, the combination with means for gripping an upper on a last, and operating means for effecting relative movement of said gripping means and the last to pull the upper, of supplemental power operated means constructed and arranged to effect subsequently a plurality of positive relative movements of said gripping means and the last in time relation for relaxing and increasing alternately the tension of the upper. 110
6. In a machine of the class described, the combination with means for gripping an upper on a last, and operating means for effecting relative movement of said gripping means and the last to pull the upper, of supplemental power operated means arranged for operation after said first operating means has come to a stop and constructed to effect a plurality of relative movements of said upper gripping means and the last in time relation for relaxing and increasing alternately the tension of the upper. 120
7. In a machine of the class described, the combination with means for gripping an upper on a last, and means for effecting relative movement of said gripping means and the last to pull the upper, of supplemental power operated means having a determinate cycle of operations to effect subsequently a positive relative movement of said gripping means and the last to relax the tension of the upper and then to cause reverse relative movement of the gripping means and the last to pull the upper first yieldingly and then positively. 130
8. In a machine of the class described, the combination with means for gripping an upper on a last, and means for effecting relative movement of said gripping means and the last to pull the upper, of supplemental power operated means arranged to be started in operation after the upper has been pulled and constructed to effect a positive relative movement of said gripping means and the last to relax the tension of the upper and then automatically to reverse the relative movement to increase the tension of the upper. 140
9. In a machine of the class described, the combination with means for gripping an upper on a last, of power driven operating means for effecting relative movements of said upper gripping means and the last in automatically determined sequence to pull the upper, then to relax the pull, and finally to subject the upper to a positive pull. 150
10. In a machine of the class described, the combination with means for gripping an upper on a last, of power driven operating means constructed and arranged to effect in automatically determined sequence a yielding relative movement of said upper gripping means and the last to pull the upper, then a positive relative movement to relax the pull, and then a positive relative movement to pull the upper again. 160
11. In a machine of the class described, the combination with means for gripping an upper on a last, and means for effecting relative movement of said gripping means and the last to pull the upper, of supplemental power operated means for effecting subsequently a plurality of relative movements of said gripping means and the last in time relation for relaxing and increasing alternately the tension of the upper, and means for varying the extent of the relative movements effected by said supplemental power means. 170
12. In a machine of the class described, the combination with means for gripping an upper on a last, and operating means for effecting relative movement of said gripping means and the last to pull the upper, of supplemental power operated means arranged to effect subsequently a positive relative movement of said gripping means and the last in time relation for relaxing and increasing alternately the tension of the upper, and means for varying the extent of the relative movements effected by said supplemental power means. 180

an upper on a last, of power driven operating means including mechanism for effecting in time relation relative movements of said gripping means and the last to relax and increase alternately the tension of the upper, said mechanism being adjustable to vary independently the extent of said different relative movements.

13. In a machine of the class described, 10 the combination with means for gripping an upper on a last, of power driven means for effecting a plurality of relative movements of said upper gripping means and the last to pull the upper, and additional means for effecting a relative tension relaxing movement of said gripping means and the last in time relation to a pulling movement, said addition means being adjustable to vary the extent of said relaxing movement.

20 14. In a machine of the class described, the combination with means for gripping an upper on a last, of power driven operating means for effecting a plurality of relative movements of said gripping means and the 25 last to pull the upper and to relax the tension alternately including mechanism for effecting a final pulling movement in time relation to a relaxing movement, said mechanism being adjustable to vary the extent of 30 the final pulling movement independently of the extent of the relaxing movement.

15. In a machine of the class described, the combination with power operated means automatically operative to pull an upper 35 over a last and to come to a stop with the upper held under tension, of additional power operated means arranged to be started in operation after the upper has been pulled and automatically operative to relax and increase alternately the tension of the upper 40 and to come to a stop with the upper held under tension.

16. In a machine of the class described, the combination with power operated means 45 automatically operative to pull an upper over a last and to come to a stop with the upper held under tension, of additional power means arranged for operation after said first means has come to a stop and having a 50 determinate cycle of movements to relax and increase alternately the tension of the upper.

17. In a machine of the class described, the combination with power operated means 55 automatically operative to pull an upper over a last and to come to a stop with the upper held under tension, of independently operative power means arranged for optional use after said first means has come to a stop and having a determinate cycle of movements for relaxing and increasing alternately the tension of the upper.

18. In a machine of the class described, the combination with power operated means 60 automatically operative to pull an upper over a last and to come to a stop with the

upper held under tension, of additional power means arranged to be operated after the upper has been pulled and having a determinate cycle of movements for positively relaxing and for then positively increasing 70 the tension of the upper.

19. In a machine of the class described, the combination with power operated means automatically operative to pull an upper over a last and to come to a stop with the upper held under tension, and means automatically operative upon a subsequent starting of the machine to overlay and fasten the upper, of additional power means arranged for operation in the interval between the upper pulling operation and the overlaying and fastening operations and having an automatically determined cycle of movements to relax and increase alternately the tension of the upper.

20. In a machine of the class described, the combination with power operated means automatically operative to pull an upper over a last and to come to a stop with the upper held under tension, and means automatically operative upon a subsequent starting of the machine to overlay and fasten the upper, of additional power means arranged for optional use in the interval between the upper pulling operation and the overlaying and fastening operations and having a determinate cycle of operations for relaxing the tension of the upper and for then causing an increase of the tension first yieldingly and then positively.

21. In a machine of the class described, the combination with a plurality of grippers for engaging an upper on a last, and means for effecting relative movement of said grippers and the last to pull the upper, of supplemental power operated means for effecting subsequently a plurality of relative movements of said grippers and the last in time relation for relaxing and increasing alternately the tension of the upper.

22. In a machine of the class described, the combination with a plurality of grippers for engaging an upper on a last, and power operated means for effecting relative movement of said grippers and the last to pull the upper to approximately the final tension, of supplemental power operated means arranged for operation after said first power means has come to a stop to effect relative movement of the several grippers and the last to vary determinately the tension of the upper and to come automatically to a stop with the upper held under tension.

23. In a machine of the class described, the combination with grippers for engaging an upper at opposite sides of a last, and means for effecting relative movement of said grippers and the last to pull the upper transversely of the last, of supplemental power operated means arranged for oper-

- ation after said first means has come to a stop to effect a plurality of relative movements of said grippers and the last in time relation for relaxing and increasing alternately the transverse tension of the upper.
24. In a machine of the class described, the combination with grippers for engaging an upper respectively at the toe end and at opposite sides of a last, and means for effecting relative movement of said grippers and the last to pull the upper both longitudinally and transversely, of supplemental power operated means arranged for operation after said first named means has come to a stop and constructed to effect a plurality of relative movements of said grippers and the last in time relation for alternately relaxing and increasing the longitudinal and transverse tensions of the upper.
25. In a machine of the class described, the combination with toe and side grippers, and power operated means for pulling an upper to approximately the final tension by relative movement of said grippers and a last, of supplemental power means arranged for use after the upper has been pulled and automatically operative to move the toe and side grippers substantially simultaneously to vary the tension of the upper and then to come to a stop with the upper held under tension.
26. In a machine of the class described, the combination with toe and side grippers, and means for pulling an upper by relative movement of said grippers and a last, of supplemental power operated means having a determinate cycle of operations to move said toe and side grippers substantially simultaneously to relax the tension of the upper and then to move them to pull the upper again.
27. In a machine of the class described, the combination with an upper engaging gripper, of power driven operating means for imparting to said gripper in determinate order an upper pulling movement, a tension relaxing movement, and a final positive upper pulling movement in time relation to the tension relaxing movement.
28. In a machine of the class described, the combination with an upper engaging gripper, of power driven operating means for imparting to said gripper in determinate order a yielding upper pulling movement, a positive tension relaxing movement, and a final positive upper pulling movement in time relation to the tension relaxing movement.
29. In a machine of the class described, the combination with toe and side grippers, of power driven operating means for imparting to all of said grippers substantially simultaneously an upper pulling movement, then a tension relaxing movement, and then another upper pulling movement.
30. In a machine of the class described, the combination with toe and side grippers, of power driven operating means constructed and arranged to impart to all of said grippers movements in determinate order first to pull the upper, then positively to relax the pull, and then again to pull the upper.
31. In a machine of the class described, the combination with toe and side grippers, of power driven operating means constructed and arranged to impart to all of said grippers movements in determinate order first to pull the upper yieldingly, then positively to relax the pull, and then positively to pull the upper again.
32. In a machine of the class described, the combination with a gripper and means for operating it to pull an upper over a last, of supplemental power operated means arranged to be started in operation after the upper has been pulled and constructed to impart to said gripper additional movements in time relation for relaxing and increasing alternately the tension of the upper.
33. In a machine of the class described, the combination with a gripper, and means for operating it to pull an upper over a last, of supplemental power operated means for imparting to said gripper subsequently in time relation positive movements for relaxing and increasing alternately the tension of the upper.
34. In a machine of the class described, the combination with a gripper, and means for operating it to pull an upper over a last, of supplemental power operated means arranged for operation after said first means has come to a stop and constructed to impart to said gripper in time relation a tension relaxing movement and a tension applying movement.
35. In a machine of the class described, the combination with a gripper and means for operating it to pull an upper over a last, of supplemental power operated means arranged for optional use after the upper has been pulled and having a determinate cycle of operations first to cause the gripper to relax the tension of the upper and then to move it in a direction to increase the tension.
36. In a machine of the class described, the combination with a gripper, and power means automatically operative to move said gripper to pull an upper over a last and then to come to a stop with the upper held under tension, of independently operative power means arranged for use after the upper has been pulled and constructed to impart to the gripper in time relation movements to relax and then to increase the tension of the upper.
37. In a machine of the class described, the combination with a gripper, and means

- including an updraw spring for imparting upper pulling movement yieldingly to said gripper, of supplemental power operated mechanism having a determinate cycle of 5 operations for moving the gripper subsequently against the resistance of its spring to relax the pull on the upper and for then releasing it to the action of its spring and for finally moving the gripper positively 10 in the direction to tension the upper.
38. In a machine of the class described, the combination with a gripper, and power means including an updraw spring for imparting upper pulling movement yieldingly 15 to said gripper, of additional power means arranged for operation after said first means has come to a stop and constructed to impart to said gripper positive movements in automatically determined sequence for relaxing 20 and increasing alternately the tension of the upper.
39. In a machine of the class described, the combination with a gripper, a gripper lever, and means connected to said lever for 25 moving the gripper to pull an upper, of supplemental power operated means independently connected to said lever and having an automatically determined cycle of operations for moving the gripper alternately 30 in opposite directions to relax and increase respectively the tension of the upper.
40. In a machine of the class described, the combination with a gripper and means for operating it to pull an upper over a last, 35 of supplemental gripper operating means comprising a cam shaft and cam means thereon for moving the gripper in opposite directions for relaxing and increasing alternately the tension of the upper.
41. In a machine of the class described, the combination with a gripper and means for operating it to pull an upper over a last, 40 of supplemental gripper operating means comprising a cam shaft with cam means thereon for moving said gripper subsequently 45 in opposite directions for relaxing and increasing alternately the tension of the upper, and clutch means for controlling the operation of said cam shaft.
42. In a machine of the class described, the combination with a gripper and means for operating it to pull an upper over a last, 50 of supplemental gripper operating means comprising a cam shaft with cam means thereon for moving said gripper in opposite directions after said first means has come to a stop for relaxing and increasing alternately 55 the tension of the upper, manual means for starting the operation of said cam shaft, and mechanism automatically operative to stop said shaft at the end of a single revolution.
43. In a machine of the class described, the combination with a gripper and means 60 for operating it to pull an upper over a last, of supplemental gripper operating means comprising a cam for moving the gripper in a direction to relax the tension of the upper, and a member connected to said gripper to be moved by the gripper operating means 70 toward said cam in the upper pulling operation and arranged to be acted upon subsequently by the cam to impart to the gripper a tension relaxing movement.
44. In a machine of the class described, 75 the combination with a gripper, a gripper lever, and means for operating said lever to pull an upper over a last, of supplemental power driven gripper operating means comprising an operating lever connected to said gripper lever, and a cam for moving said operating lever in a direction to cause the gripper to relax the tension of the upper.
45. In a machine of the class described, 80 the combination with a gripper and means for operating it to pull an upper over a last, of supplemental gripper operating means comprising cams arranged to act successively after said first means has come to a stop to move said gripper first in a direction to 85 relax the tension of the upper and then in a direction to increase the tension.
46. In a machine of the class described, 90 the combination with an upper engaging gripper, of power driven operating means for moving said gripper alternately to pull and to relax the tension of the upper including a pawl and ratchet device to impart a final positive pull to the gripper.
47. In a machine of the class described, 95 the combination with an upper engaging gripper, of power driven operating means for moving said gripper alternately to pull and to relax the tension of the upper including a pawl and ratchet device to impart a final positive pull to the gripper, said pawl and ratchet device being adjustable to vary the extent of the final pull.
48. In a machine of the class described, 100 the combination with a gripper and means for operating it to pull an upper over a last, of supplemental power driven gripper operating means constructed to move the gripper in a direction to relax the tension of the upper and including a pawl and ratchet device for moving the gripper finally 105 in a direction to increase the tension.
49. In a machine of the class described, 110 the combination with a gripper and means for operating it to pull an upper over a last, of supplemental gripper operating means comprising an operating member connected to the gripper, a cam shaft, a cam on said shaft for moving said member in a direction to relax the tension of the upper, a pawl and ratchet device for moving 115 said member in the opposite direction to increase the tension, and a second cam on said shaft for operating the pawl and ratchet device.
50. In a machine of the class described, 120 the combination with a gripper and means for operating it to pull an upper over a last, of supplemental gripper operating means comprising an operating member connected to the gripper, a cam shaft, a cam on said shaft for moving said member in a direction to relax the tension of the upper, a pawl and ratchet device for moving 125 said member in the opposite direction to increase the tension, and a second cam on said shaft for operating the pawl and ratchet device.

50. In a machine of the class described, the combination with a gripper and means for operating it to pull an upper over a last, of supplemental power driven gripper operating means having a determinate cycle of operations to move said gripper subsequently in opposite directions for relaxing and increasing alternately the tension of the upper, said supplemental operating means being adjustable to vary the extent of movement of the gripper in said opposite directions.

51. In a machine of the class described, the combination with a gripper and means for operating it to pull an upper over a last, of supplemental gripper operating means comprising an operating member connected to the gripper and having ratchet teeth thereon, power means for moving said member in a direction to cause the gripper to relax the tension of the upper, a power operated pawl for engaging said ratchet teeth and moving the member in the opposite direction to increase the tension, and controlling means for said pawl to hold it out of engagement with said ratchet teeth when said member is moved to relax the tension.

52. In a machine of the class described, the combination with toe and side grippers, and operating means for effecting relative movements of said grippers and a last to pull an upper, of supplemental power driven means arranged for operation after said first named means has come to a stop to impart to the toe gripper in time relation alternate tension relaxing and tension applying movements.

53. In a machine of the class described, the combination with grippers for engaging an upper respectively at opposite sides of a last, and means for operating said grippers to pull the upper, of supplemental gripper operating means arranged for operation after said first named means has come to a stop, said supplemental means being constructed to impart to said grippers a plurality of movements in time relation for relaxing and increasing alternately the tension of the upper.

54. In a machine of the class described, the combination with grippers for engaging an upper at opposite sides of a last, and operating means for moving said grippers to pull the upper, of supplemental power driven gripper operating means constructed to impart subsequently to both said grippers simultaneously a positive movement to relax the tension of the upper and then automatically to reverse said movement to increase the tension.

55. In a machine of the class described, the combination with grippers for engaging an upper respectively at opposite sides of a last, and operating means for mov-

ing said grippers to pull the upper, of supplemental gripper operating means comprising a member connected to both said grippers, and power means having a determinate cycle of operations to move said member successively in opposite directions for relaxing and increasing alternately the tension of the upper.

56. In a machine of the class described, the combination with grippers for engaging an upper respectively at opposite sides of a last, and operating means for moving said grippers to pull the upper, of supplemental gripper operating means comprising a pivotally mounted lever, power driven mechanism for moving said lever alternately in opposite directions, and connections between said lever and both side grippers for imparting movements to both grippers simultaneously to relax and increase alternately the tension of the upper.

57. In a machine of the class described, the combination with grippers for engaging an upper respectively at opposite sides of a last, and operating means for moving said grippers to pull the upper, of supplemental gripper operating means comprising a member connected to both said grippers, a cam shaft, and cams on said shaft for moving said member successively in opposite directions to relax and increase alternately the tension of the upper.

58. In a machine of the class described, the combination with opposite side grippers, gripper levers, and operating means for moving said levers to pull an upper, of supplemental gripper operating means comprising a pivotally mounted operating lever, link connections between said lever and the gripper levers, a cam for moving said operating lever in one direction for relaxing the tension of the upper, and pawl and ratchet mechanism automatically operative in time relation to said cam to move said lever in the opposite direction for increasing the tension of the upper.

59. In a machine of the class described, the combination with grippers for engaging an upper on a last, and power means automatically operative to impart upper pulling movement to said grippers and to come to a stop with the upper held under tension, of supplemental gripper operating means arranged to be controlled independently of said first means and having an automatically determined cycle of operations to impart to said grippers additional movements alternately in opposite directions for relaxing and increasing respectively the tension of the upper.

60. In a machine of the class described, the combination with grippers for engaging an upper on a last, and operating means comprising a cam shaft for imparting upper pulling movement to said grippers, of sup-

plemental gripper operating means comprising a power driven cam shaft arranged to be controlled independently of said first named shaft for imparting to the grippers 5 subsequently movements alternately in opposite directions for relaxing and increasing respectively the tension of the upper.

61. In a machine of the class described, the combination with grippers for engaging an upper on a last, and power means comprising a cam shaft for imparting upper pulling movement to said grippers, of supplemental gripper operating means comprising a power driven cam shaft extending 10 in transverse relation to said first named shaft and having operating cams thereon, and connections to the different grippers arranged to be operated by said cams for imparting supplemental movements to said 15 grippers.

62. In a machine of the class described, the combination with toe and side grippers, and rotatable power means for imparting upper pulling movement to said grippers, 25 of supplemental gripper operating means comprising a cam for imparting to the toe gripper movement to alter the tension of the upper, and an additional cam for imparting to both side grippers in unison 30 movement to alter the tension.

63. In a machine of the class described, the combination with toe and side grippers, and operating means for imparting upper pulling movement to said grippers, of supplemental gripper operating means comprising cams for imparting to the toe gripper movements alternately in opposite directions for relaxing and increasing respectively the longitudinal tension of the upper, 40 and additional cams for imparting to the side grippers movements alternately in opposite directions for relaxing and increasing the transverse tension of the upper.

64. In a machine of the class described, 45 the combination with toe and side grippers, gripper levers, and operating means for imparting upper pulling movement to said levers, of supplemental operating means comprising pivotally mounted levers one of 50 which is connected to the toe gripper lever and the other to both the side gripper levers, and power driven means for imparting to said operating levers movements alternately in opposite directions for relaxing and increasing respectively the tension of the upper.

65. In a machine of the class described, 55 the combination with a gripper, of a gripper operating member, a cam roll on said member, and a cam for engaging said roll to operate the gripper, said cam roll being adjustable to vary the extent of movement of the gripper.

66. In a machine of the class described, 60 the combination with a gripper, of an op-

erating member connected to said gripper and having ratchet teeth thereon, a pawl carrier provided with a pawl for engagement with said teeth, power means for imparting a determinate movement to said pawl carrier, 70 and a controlling device for holding said pawl initially out of engagement with the ratchet teeth and for releasing it in response to movement of the pawl carrier to permit it to engage said teeth, said controlling device 75 being adjustable to vary the time of engagement of the pawl with the ratchet teeth and thus to vary the extent of movement of the gripper.

67. In a machine of the class described, 80 the combination with a gripper, of an operating member connected to said gripper and having ratchet teeth thereon, a power driven cam shaft provided with a cam for moving said member in one direction to operate the gripper, a pawl carrier provided with a pawl for engagement with said ratchet teeth to move said member in the opposite direction, and a cam on said cam shaft for imparting operative movement to said pawl carrier. 85

68. In a machine of the class described, 90 the combination with upper engaging grippers, and operating means for said grippers including springs arranged to be differently stressed in proportion to differences in the extent of movement of the different grippers, 95 of supplemental gripper operating means comprising connections to the grippers for moving them subsequently to relax the force of the pull on the upper, said connections being arranged to compensate automatically for differences in the stresses of the respective springs to assist in preventing a balancing action between the springs when the pull is relaxed. 100

69. In a machine of the class described, 105 the combination with opposite side grippers, and operating means for said grippers including springs arranged to be differently stressed in proportion to differences in the extent of movement of the different grippers, 110 of supplemental gripper operating means comprising an operating member and operating connections between said member and the respective grippers, said connections 115 being relatively movable in the upper pulling operation and arranged to compensate automatically for differences in the stresses of the respective springs to assist in preventing a balancing action between said 120 springs in the operation of the supplemental means.

70. In a machine of the class described, 125 the combination with opposite side grippers, and operating means for said grippers including springs arranged to be differently stressed in proportion to differences in the extent of movement of the different grippers, 130 of supplemental gripper operating means comprising an operating member and oper-

ating connections between said member and the respective grippers, said connections comprising lever arms for the different respective grippers connected together and arranged to be moved in the upper pulling operation to positions in which the lever arm corresponding to the gripper spring which is under the greater stress is of a less effective length than the lever arm connected to the other gripper.

71. In a machine of the class described, the combination with opposite side grippers, gripper levers, and operating means including springs arranged to be differently stressed in proportion to differences in the extent of movement of the different grippers, of supplemental gripper operating means comprising an operating member having a lever thereon provided with oppositely extending arms, and links connecting said arms respectively to the different gripper levers to operate them, said lever arms being arranged to assume positions of different effective length proportional to differences in the tension of the respective springs to counteract the tendency of said springs to assume a balanced relation in the operation of the supplemental means.

72. In a machine of the class described, the combination with a gripper, and means for operating it to pull an upper, of supplemental power driven gripper operating means comprising an operating member and an operating connection between said member and the gripper, and manual means arranged to operate through said connection to impart to the gripper also a movement to adjust the upper on the last.

73. In a machine of the class described, the combination with a plurality of grippers, and means for operating said grippers to pull an upper, of supplemental power driven gripper operating means comprising connections through which to move the grippers subsequently to vary the tension of the upper, and manual means arranged to operate through said connections for imparting to the grippers also movements for adjusting the upper on the last.

74. In a machine of the class described, the combination with opposite side grippers, and means for operating said grippers to pull an upper, of supplemental power driven gripper operating means comprising connections through which to move the grippers subsequently to vary the tension of the upper, and manual means arranged to operate through said connections to impart to the opposite side grippers also movements simultaneously in opposite directions for shifting the upper transversely of the last.

75. In a machine of the class described, the combination with opposite side grippers, and means for operating said grippers to pull an upper, of supplemental power driven

gripper operating means comprising a movable operating member, operating connections between said member and the respective grippers arranged to permit movement of the grippers relatively to each other, and manual means arranged to operate through said connections to move the opposite side grippers also simultaneously in opposite directions for adjusting the upper.

76. In a machine of the class described, the combination with opposite side grippers, gripper levers, and means for operating said levers to pull an upper, of supplemental power driven gripper operating means comprising a movable operating member, a lever pivoted on said member and having oppositely extending arms, links connecting said arms respectively to the different gripper levers to operate them through the movement of said member, and manual means connected to said pivoted lever for turning it to impart to the side grippers also movements for adjusting the upper on the last.

77. In a machine of the class described, the combination with opposite side grippers and gripper levers, of gripper operating means comprising a movable operating member, a lever pivotally mounted on said member and having oppositely extending arms, links connecting said arms respectively to the different gripper levers to operate them through the movement of said member, a third arm connected to said oppositely extending arms, and a hand lever connected to said third arm for imparting to the opposite side grippers also movements simultaneously in opposite directions for adjusting the upper.

78. In a machine of the class described, the combination with opposite side grippers, of gripper operating means comprising a movable operating member, a lever pivotally mounted on said member and having oppositely extending arms, links connecting said arms respectively to the different grippers to operate them through the movement of said member, a manually operated member connected to said lever for turning it to move the side grippers also simultaneously in opposite directions for adjusting the upper, and a friction device associated with said manual member to assist in retaining the grippers in adjusted position.

79. In a machine of the class described, the combination with a plurality of grippers, and gripper operating means including springs arranged to be differently stressed in proportion to differences in the extent of movement of the different grippers, of supplemental gripper operating means comprising connections to said grippers arranged to compensate automatically for differences in stress of the different springs to assist in preventing balancing ac-

tion of said springs, and additional means arranged to operate through said connections to move the grippers also relatively for adjusting the upper.

- 5 80. In a machine of the class described, the combination with opposite side grippers, and gripper operating means including springs arranged to be differently stressed in proportion to differences in the 10 extent of movement of the different grippers, of supplemental power driven gripper operating means comprising connections to said grippers arranged to compensate automatically for differences in stress of the 15 different springs to assist in preventing balancing action of said springs, and manual means arranged to operate through said connections to move the side grippers also simultaneously in opposite directions for adjusting the upper.

- 20 81. In a machine of the class described, the combination with opposite side grippers, and operating means including springs arranged to be differently stressed in proportion 25 to differences in the extent of movement of the different grippers, of supplemental gripper operating means comprising connections to said grippers arranged to compensate automatically for differences in 30 stress of the different springs to assist in preventing balancing action of said springs, manual means arranged to operate through said connections to impart to the opposite side grippers movements simultaneously in 35 opposite directions for adjusting the upper, and a friction device associated with said manual means to assist in preventing balancing action of the gripper springs.

82. In a machine of the class described, 40 the combination with opposite side grippers, gripper levers, and operating means including springs arranged to be differently stressed in proportion to differences in the extent of movement of the different grippers, of supplemental power driven gripper operating means comprising a movable operating member, a lever pivotally mounted on said member and having oppositely extending arms connected respectively to the 45 different gripper levers to operate them through the movement of said member, said arms being arranged to assume positions of different effective length to compensate for differences in the stresses of the different 50 springs, and manual means for also turning said lever to move the opposite side grippers simultaneously in opposite directions for adjusting the upper transversely of the last.

83. In a machine of the class described, 60 the combination with means for gripping an upper on a last, and operating means for effecting relative movement of said gripping means and the last to pull the upper, of supplemental operating means having a determinate cycle of power movements for re-

laxing and increasing alternately the tension of the upper, and controlling mechanism to cause said supplemental operating means to repeat its cycle of movements.

84. In a machine of the class described, 70 the combination with means for gripping an upper on a last, and operating means for effecting relative movement of said gripping means and the last to pull the upper, of supplemental operating means having a determinate cycle of power movements for relaxing and increasing alternately the tension of the upper, a device automatically operative to bring said supplemental operating means to a stop at the end of its cycle, 75 and manual means for rendering said stopping device inoperative and for thereby causing a repetition of said cycle.

85. In a machine of the class described, the combination with means for gripping an upper on a last, and operating means for imparting upper pulling movement to said gripping means, of supplemental power driven means arranged for operation subsequently to impart to said gripping means 80 relaxing and pulling movements in determinate order, and clutch mechanism arranged for both automatic and manual control to bring said supplemental power means to a stop at a determinate point or to continue it in operation at the will of the operator.

86. In a machine of the class described, the combination with grippers and means for operating them to pull an upper over a 100 last, of supplemental operating means for said grippers comprising a cam shaft and cam means thereon for moving the grippers alternately in opposite directions to relax and then to increase the tension of the upper, a clutch through which said cam shaft is operated, a member connected to the cam shaft for actuating said clutch to stop said shaft at a determinate point, and manual means for rendering said member inoperative 105 and thereby causing the cam shaft to continue in operation.

87. In a machine of the class described, the combination with means for gripping an upper on a last, of power operated means 110 for effecting a series of relative movements of said upper gripping means and the last in determinate order to pull and to relax the tension of the upper alternately, and controlling mechanism to enable the operator to vary the number of said relative movements.

88. In a machine of the class described, the combination with means for gripping an upper on a last, and power means automatically operative to effect a number of relative movements of said upper gripping means and the last and to come to a stop with the upper held under tension, of controlling mechanism to enable the operator 115 120 125 130

to vary the number of said relative movements.

89. In a machine of the class described, the combination with means for gripping an upper on a last, of power operated means having a determinate cycle of movements to operate said upper gripping means, and controlling mechanism constructed to enable the operator to determine for each shoe a number of repetitions of said cycle of movements while the gripping means maintains its hold on the upper.

90. In a machine of the class described, the combination with upper gripping means, power means having a determinate cycle of movements to operate said upper-gripping means, and overlaying and fastening means arranged to operate subsequently on the upper, of controlling mechanism constructed to enable the operator to cause a repetition of the cycle of movements of said power means to operate said gripping means a plurality of times while it maintains its hold on the upper and prior to the operation of the overlaying and fastening means.

91. In a machine of the class described, the combination with power means automatically operative to pull an upper over a last and to come to a stop with the upper held under tension, and means automatically operative upon a subsequent starting of the machine to overlay and fasten the

upper, of supplemental power means automatically operative at the will of the operator in the interval between said upper pulling operation and the overlaying and fastening operations to vary determinately the tension of the upper and to come to a stop with the upper under tension, and controlling mechanism to enable the operator to vary the number of operations of said supplemental means upon the upper.

92. In a machine of the class described, the combination with power means automatically operative to pull an upper over a last and to come to a stop with the upper held under tension, and means automatically operative upon a subsequent starting of the machine to overlay and fasten the upper, of supplemental power means arranged for operation in the interval between said upper pulling operation and the overlaying and fastening operations and having a determinate cycle of movements to relax and increase alternately the tension of the upper, and controlling mechanism to enable the operator to determine for each shoe a number of repetitions of the cycle of movements of said supplemental means.

In testimony whereof we have signed our names to this specification.

CHARLES FAWCETT BENNION.

JOSEPH GOULDBOURN.

ARTHUR BATES.
